UNITED STATES PATENT OFFICE.

LEANDER A. COGSWELL, OF MANCHESTER, NEW HAMPSHIRE, ASSIGNOR TO LACENE MANUFACTURING COMPANY, OF MANCHESTER, NEW HAMPSHIRE, A CORPORATION OF MAINE.

GRADING MACHINE.

Application filed March 18, 1927. Serial No. 176,415.

This invention relates to grading machines of the kind which grade died-out pieces of leather such as cut soles, taps, heel lifts, counters or other blanks, in accordance with the thickness of the thinnest spot as determined by the detector.

The present invention consists chiefly in certain improvements upon the grading machine illustrated in Letters Patent of the United States No. 1,582,140, issued April 27, 1926, to Lacene Manufacturing Company upon the invention of Elmer P. Nichols. The present machine, like said Nichols machine, is designed merely to grade blanks by means of a pointer or indicator, which shows the grade of the several blanks as they pass successively through the machine, without skiving or evening, marking or sorting them.

In said Nichols machine the blanks were inserted into the machine one by one by hand, and after their grade was determined they were removed from the machine by hand and then distributed. The principal object of the present invention is to provide feeding mechanism which is automatically operated to feed in a new blank from a magazine containing ungraded blanks when the operator removes a graded blank from the machine. The feeding mechanism is normally idle and is actuated only when the operator removes the graded blank so that the timing of the feeding in of the new blank, as well as the restoration of the indicator to a condition in which it is ready to respond to a new blank, is wholly under the control of the operator. This allows the operator a greater or less amount of time as he may require for observing and reading the indicated grade of a graded blank before the indicator is disturbed and another blank is fed in; but it also increases the ease and speed of operation in that when the operator has removed a graded blank and while he is engaged in distributing or disposing of the same, another blank is automatically being fed into the machine without attention on his part. Other novel features will appear as the description proceeds.

In the accompanying drawings:

Fig. 1 is a plan view of my improved grading machine;

Fig. 2 is a side elevation on an enlarged

scale of a portion of the machine shown in Fig. 1;

Fig. 3 is a section on line 3—3 of Fig. 1;

Fig. 4 is a section on line 4—4 of Fig. 1;

Fig. 5 is a partial section on line 5—5 of Fig. 1; and

Fig. 6 is a section on line 6—6 of Fig. 2.

Referring to the drawings, 1 represents the main shaft of the machine which is also the shaft of the upper, fixed detecting roll 2. The shaft 1 has loosely mounted on it a sprocket wheel 3 (Fig. 4) at each side of which is a fiber washer 4, said shaft being threaded to receive upon it two nuts 5 by means of which the sprocket wheel 3 is clamped firmly between the two fiber washers 4, 4 and thereby frictionally connected with the shaft 1.

The shaft 1 also has loosely mounted on it a worm gear 6 continuously driven by a worm 7 fast on the armature shaft 8 of a motor 9, said motor being mounted upon a bracket 10 projecting from the side of the frame of the machine. The inner end of the hub of worm gear 6 is formed with radial sockets to receive radial tongues 11 provided upon a collar 12 mounted upon the shaft 1 (Figs. 1 and 4). The inner end of this collar 12 is formed with one or more notches 13 occupied by the end, or ends, of a pin 14 extending through the shaft 1. In this way the worm gear 6 is locked to the collar 12 and the collar 12 is locked to the shaft 1 so that normally all three of these parts are continuously rotated by the motor 9. The notch 13 is stepped so that by shifting the pin 14 angularly therein the collar 12 can be slid on shaft 1 away from the hub of worm gear 6 to uncouple shaft 1 from said gear when it is desired to turn the machine over by hand. The machine is turned over by hand by first uncoupling the gear 6 from the shaft as described and then applying a wrench or other tool to the squared outer end of the shaft 1.

The shaft 1 of the upper, fixed, detecting roll 2 carries gears 15, meshing with gears 16, fast on the shaft of the lower, yielding, detecting roll 17, so that the two detecting rolls are continuously rotating when the machine is in operation.

The soles, taps or other blanks which are to be graded are stacked within a hopper or magazine H, (Fig. 3) from which they

are automatically fed, one at a time, to the detecting rolls 2 and 17.

The lower detecting roll 17 is supported at its ends in the forward ends of two arms 18, one at each side of the machine, whose rear ends are formed with longitudinal trunnions 19 (Fig. 1) mounted to swivel in bearing blocks 20, each having trunnions 21 (Fig. 2) at opposite sides thereof mounted 10 in bearings on the frame of the machine so as to rock on a transverse axis. This provides a universal joint at the rear end of each arm 18 to accommodate the necessary up and down independent feeding or detecting movements of the opposite ends of the lower roll 17 in response to the unevenness of the blanks as they pass between the detecting rolls.

Connecting the forward ends of the arms 20 18 is a cross bar 22 (Fig. 4) pressed strongly upward by two bell crank levers 23 fulcrumed at 24 on the frame of the machine and having their depending arms connected by a spring 25 which is normally under 25 stress.

Each arm 18 has connected to its forward end the upper end of a rod 26 which extends downwardly between a pair of lugs 26' projecting from the adjacent side of the frame 30 of the machine. Adjustably secured to the lower end of each rod 26, by means of nuts 27, is an inwardly projecting bracket arm 28, and to the inner ends of these two arms, which are bifurcated, are pivotally connected, at 29, the opposite ends of a cross bar 30. The pivotal connections between the cross bar 30 and bracket arms 28 permit either rod 26 to move vertically independently of the other in response to tilting 35 movements of the lower detecting roll 17. To limit the upward movements of the rods 26 the latter are provided with nuts 31 and washers 32 to engage the under sides of the lugs 26' on the frame of the machine.

40 Resting on the cross bar 30 are the rear ends of arms 33 fixed to, and projecting rearwardly from, a rock shaft 34 journaled near its ends in bearings on the frame of the machine. At one side of the machine 45 (Figs. 2 and 4) the rock shaft 34 extends outside of the frame and has fastened thereto a relatively long arm 35 whose rear end is formed with a vertical hole through which extends the lower end of a rod 36, said rod being provided, immediately below the arm 35, with a head 37 which is yieldingly held against said arm by a spring 38 mounted on rod 36, the upper end of said spring bearing against an abutment collar 39 adjustably 50 secured to the rod 36.

The upper end of the rod 36 is pivotally connected at 40 to a gear segment 41, pivoted at 42 on the frame of the machine. This segment 41 meshes directly with a pinion 43 on whose shaft 44 is fixed a pointer 45

(Fig. 5), said shaft 44 being concentric with the scale or dial 46 fixed to the frame of the machine. The scale 46 is graduated in "irons" and is traversed by the pointer 45 when the shaft 44 is rotated. Also fixed to the shaft 44 are two ratchet wheels 47 and 48 cooperating, respectively, with two pawls 49 and 50, both pivoted at 51 on the frame of the machine. A spring 52 yieldingly urges the pawl 49 towards its ratchet wheel 47, and a spring 53 (Fig. 1) yieldingly urges the pawl 50 towards its ratchet wheel 48. Pawl 49 is in the form of a bell crank lever and carries a laterally projecting pin 54 cooperating with an arm 55 fast 55 on a rock shaft 56, journaled at its ends in bearings on the frame of the machine.

Near its middle, this rock shaft 56 is provided with a rearwardly extending horizontal arm 57 disposed above the table 58 upon which the soles or other blanks are delivered by the detecting rolls. The arm 57 has adjustably secured to it a depending bracket 59 (Figs. 2 and 3) carrying at its lower end a trip in the form of a narrow roll 60 60 which rests in a channel or groove 61 formed in a narrow, elevated runway or work support 62 provided upon the top side of table 58 and extending rearwardly from the detecting rolls 2 and 17. The table 58 is horizontal but the narrow, grooved runway 62 increases in height progressively and uniformly from the detecting rolls rearwardly. The bottom of the groove 61 is also horizontal and parallel with arm 57, so that it will be clear that the bracket arm 59 may be adjusted longitudinally of the arm 57 without disturbing the position of the latter, or of the arm 55 on the rock shaft 56. As a sole or other blank leaves the detecting rolls 65 2 and 17 it passes up the runway 62 and underneath the roll 60 thereby raising the latter. The purpose of the inclined grooved runway and the progressively increasing depth of channel 61 is to provide for substantially the same angular movement of the arm 57, by a sole or other blank of given thickness, no matter where the bracket 59 and roll 60 may be positioned on the said arm 57 with relation to rock shaft 56.

The passage of the advance end of a sole or other blank under trip roll 60 results in locking pointer 45 so that it can not thereafter be operated to indicate a thicker spot in the blank, but can only move toward the left (Fig. 5) in a direction to indicate the measurement of a thinner spot in the blank being graded. Until the forward end of the blank has reached and lifted the trip roll 60, the indicating mechanism does not usefully preserve any of the grade measurements, but after the leading end of the piece of stock has reached and raised the roll 60, all that portion of the blank which thereafter passes between the detecting rolls 2 and 17, is graded 125 130

but only with reference to the thinnest portion encountered by the detecting rolls. That is, after the forward end of the blank raises the trip roll 60, thereby engaging the pawl 49 with its ratchet, the pointer 45 can be moved by the detecting rolls only in a direction to indicate the thickness of portions of the blank that are thinner than the portion occupying a position between the detecting rolls at the moment that the pawl 49 was moved into engagement with its ratchet wheel 47. By adjusting the trip 60 on arm 57 the machine may be caused to grade only a particular or selected portion of the blank, for example, the forepart of a sole to the exclusion of the heel part, the sole being fed to the detecting rolls heel end first. Hence, by setting the bracket 59 and trip 60 at a distance from the detecting rolls corresponding to the length of the heel and shank portions of the sole, those parts will not be graded but the rest of the sole will be graded.

The bottom of the hopper H is formed by the shelf or table 63 fastened to the machine frame and extending up close to the detecting rolls. Immediately in front of the detecting rolls is a vertically movable trip 64 mounted to slide freely in a bearing provided on a fixed part of the frame, the lower end of this feeler 64 resting by gravity upon the top of the table 63 in the path of the blanks as they are fed toward the detecting rolls. The upper end of the trip 64 is provided with a double yoke 65 which embraces one end of a lever 66 fulcrumed at 67 on a fixed part of the frame and having its opposite end cooperatively disposed with relation to one arm of a bell crank 68 fulcrumed at 69 on the frame of the machine (Figs. 2, 4 and 5), the other arm of this bell crank being connected by a link 70 with the upper end of the pawl 50 (Fig. 5). When a blank is automatically fed forward from the hopper H, as herein-after described, the trip 64 is automatically lifted to permit the passage of the forward end of the blank under the trip, whereupon it is immediately dropped so as to rest on top of the blank while the latter is passing between the detecting rolls. When thus lifted by the forward feeding motion of the feed mechanism, the trip 64 acts through yoke 65, lever 66, bell crank 68 and link 70 to disengage the pawl 50 from its ratchet wheel 48, thus allowing the spring 38 to restore the pointer 45 to zero position, there being no blank under trip 60. It will be understood that when the trip 64 is thus lifted to admit a blank to the detecting rolls, the preceding blank has passed beyond the detecting rolls, and therefore the lower detecting roll 17 occupies its position of closest approach to the upper detecting roll 2 where it is held by the heavy spring 25. It will

also be clear that at the moment trip 64 is lifted the arm 35 through its connections with the arms 18, will be held in an elevated position away from head 37 with spring 38 under compression because of the engagement of pawl 50 with its ratchet wheel. Consequently, when latch 50 is moved out of engagement with its ratchet wheel, as described, spring 38 will restore the pointer 45 to its zero position.

A relatively light spring 71 (Fig. 2) having its upper end connected with the frame of the machine and its lower end with the arm 35, yieldingly urges the two arms 33 towards the cross bar 30. This spring 71, however, is dominated by the heavy spring 25.

Throughout the time that the blank is passing under the trip 64 the latch 50 is held in its inoperative position but as soon as the blank passes beyond the trip 64 at the end of the detecting and indicating operations, said trip 64 falls and acts through the connections described to return the pawl 50 into engagement with its ratchet wheel 48, thereby locking the pointer 45 against movement thereafter toward zero position. This reengagement of pawl 50 with its ratchet wheel does not occur, however, until after nearly all of the blank has passed between the detecting rolls. At some time prior to this, for example, when the detecting rolls reach the junction of the forepart with the heel or shank portion of the sole, the advance end of the sole lifts the trip 60 thereby effecting the engagement of pawl 49 with its ratchet wheel 47. Thereafter, while the detecting rolls are traversing the forepart of the sole, the pawl 49 is in engagement with its ratchet wheel while the pawl 50 is held out of engagement with its ratchet wheel 48. Consequently, while traversing the forepart of the sole the detecting rolls can operate the pointer 45 only in a direction to indicate a reduction in the thickness thereof, or a thickness that is less than that of the part of the sole that was between the detecting rolls at the moment the latch 49 was moved into engagement with its ratchet wheel. As soon as the rear end of the blank passes the trip 64 the latter drops upon the table 63, which results in the reengagement of pawl 50 with its ratchet wheel 48. This locks the pointer 45 against movement in either direction and it remains thus locked to indicate the thickness of the thinnest portion detected by the lower detecting roll 17, until the blank is removed by the operator from beneath the trip roll 60.

The sprocket wheel 3, mounted upon and frictionally connected with the shaft 1, is connected by a sprocket chain 72 with a sprocket wheel 73, (Figs. 2 and 6) the latter being loosely mounted upon the outer end of a relatively short shaft 74 journaled in a

bearing bracket 75 forming part of the frame of the machine. This sprocket wheel 73 is rotatably supported by the shaft 74 between a shoulder 76 and a washer 77, the inner face of said sprocket wheel being made as a clutch member 78 to cooperate with a clutch member 79 splined on the shaft 74 and movable toward and from the sprocket wheel 73. A spring 80, between the inner 10 end of clutch member 79 and the frame of the machine, yieldingly urges said member toward the sprocket wheel 73. Clutch member 79 is provided with a laterally projecting stud or pin 81 to cooperate with a cam 15 arm 82 pivoted at 83 on the frame of the machine. A spring 84 (Fig. 2) yieldingly urges said cam arm toward the clutch member 79 so that normally said cam arm is held against an adjustable stop screw 85. 20 In the drawings the cam arm 82 is shown in its uppermost position where, by engagement with the stud 81, it serves to hold the clutch member 79 out of engagement with the clutch face 78 of the sprocket 73, against 25 the pressure of spring 80.

At its right hand end (Fig. 2) the cam arm 82 is provided with an eye or loop 86 embracing the lower end of a push bar 87 having a shoulder 88 to cooperate with a 30 shoulder 89 provided at the end of cam arm 82. At its upper end the push bar 87 is pivotally connected to an arm 90 fast on rock shaft 56. It will be clear, therefore, that when the advance end of the blank raises the 35 trip 60 and arm 57 to effect the engagement of latch 49 with its ratchet wheel 47, the push bar 87 is also lifted, carrying the shoulder 88 above the shoulder 89, whereupon gravity will cause the push bar to 40 swing sidewise carrying the shoulder 88 into position directly above the shoulder 89.

When the operator removes the blank from under trip 60 for distribution, the trip 45 60 falls by gravity, and through the engagement of the shoulder 88 with the shoulder 89 the push bar 87, carried downwardly by the movement thus given to rock shaft 56, depresses the cam arm 82 below pin 81 allowing the spring 80 to shift the clutch 50 member 79 which is splined on shaft 74, into engagement with the clutch face of sprocket 73. Since the sprocket 73 is continuously driven through the chain 72 by the sprocket 3, the engagement of the clutch member 79 with the sprocket 73 will result in rotation 55 of clutch member 79 and shaft 74 in the direction of the arrow (Fig. 2). When the clutch member 79 has made about two thirds of one revolution the stud or pin 81 engages an arm 91 on push bar 87 and kicks said push bar out of engagement with the cam arm 82, whereupon spring 84 raises said cam arm into the path of pin 81 so that as the latter completes one revolution, said pin 60 rides against the side of the cam arm 82.

which, through its engagement with stud 81, acts to push the clutch member 79 out of engagement with the clutch face 78 of sprocket 3. Thus the removal for distribution of a graded blank by the operator automatically effects one revolution of the shaft 74. This causes another blank to be fed into the machine, as will now be described.

At its inner end the shaft 74 has fast to it an arm 92 connected by a link 93 with a feed carriage or slide 94 slidably mounted in ways 95 provided on the table 63. The feed slide has a feeding tooth or dog 96 projecting upwardly through a slot 97 provided in said table. It follows, therefore, that when the shaft 74 is rotated to the extent of one revolution the feed slide 94 is reciprocated and as it is moved toward the detecting rolls 2 and 17 it carries with it the lowermost sole or blank in the magazine H. At the beginning of this revolution of shaft 74 a member 97 secured to the link 93 engages the free end of lever 98, fulcrumed at 99 on the frame of the machine. The opposite end of lever 98 is connected by a link 100 with a lever 101, one end of which is fulcrumed at 102 on the frame of the machine and the other end of which is embraced by the double yoke 65 at the upper end of trip 64. The depression of lever 98 by member 97 operates through the connections described to raise the trip 64 so as to admit the blank thereunder and at the same time to actuate lever 66, bell crank 68 and link 70, to disengage pawl 50 from its ratchet wheel 48, thus allowing the spring 38 to return the pointer 45 to its zero position (from the position to which it was moved by the preceding sole or the like) preparatory to grading the blank being fed forward by the feed 105 slide 94.

The usual upwardly yielding spring pressed detent 103 is provided immediately in front of the detecting rolls 2 and 17 which serves to prevent more than one blank from being fed forward at one time. An example of such spring pressed detent is shown in my Patent No. 1,433,873 dated October 31, 1922.

In the event of the clogging of blanks in the magazine, tending to resist the movement of feed slide 94, the frictional connection between the sprocket 3 and shaft 1 yields, thus avoiding breakage of parts, but under normal conditions this frictional connection is strong enough to operate the feed slide.

The hopper, or magazine H, comprises a floor formed by the shelf or table 63 secured to the main frame of the machine, said floor being made with ways in which the feed slide 94 is mounted and with a slot 97 through which the dog 96 projects upwardly to engage the soles or the like. The magazine also comprises two upstanding end walls 103 and 104 to each of which is adjustably

secured a pair of upstanding side walls or guides 105 and 106. The end wall 104 is fastened in a fixed position by screws 107 (Fig. 3) which secure it to the frame of the machine, while the end wall 103 is fastened in a position on the shelf 63 by a bolt 108 with provision for adjustment toward and from the end wall 104, said bolt extending through a slot 109 provided in shelf 63. The side guides 105 and 106 on wall 103 (Fig. 1) are provided with angular arms having tapped holes near their ends, the tapped hole of one arm having a right-hand thread and the tapped hole of the other arm having a left hand thread. Through the holes of these two arms extends a screw shaft 110 having appropriately threaded end portions engaging the threaded holes of the arms. The threaded shaft 110 has a bearing in a bracket 111 secured to the outer side of the end wall 103, and near its middle the shaft is made with an annular groove into which projects the inner end of a screw 112 to hold the shaft against endwise movement, but free to rotate. At one end shaft 110 is provided with a hand wheel 113 by means of which it is manually rotated to adjust the side guides 105 and 106 toward and from each other. Near their lower ends the side guides are provided with laterally projecting lugs 114 sliding in transverse grooves provided upon the inner face of end wall 103.

The side walls or guides 105 and 106 of wall 104 are also provided with laterally extending angular arms, each provided near its extremity with a threaded hole, the hole of one arm being tapped with a left-hand thread and the hole of the other arm being tapped with a right-hand thread. Through the holes of the two arms extends a screw shaft 115 whose opposite end portions are appropriately formed with right and left-hand threads, respectively. Near its middle the screw shaft 115 has a bearing in a bracket 116 secured to the outer side of end wall 104; this bracket is formed with a slot occupied by a latch 117, said latch engaging one of a series of annular grooves 118 provided upon the screw shaft 115 to hold the latter against endwise movement. The latch 117 is pivoted at 119 upon a lug projecting from end wall 104 and is acted upon by a spring 120 which holds the latch in engagement with the screw shaft. Screw shaft 115 is provided at one end with a hand wheel 121, and as will be clear, said shaft is free to be rotated manually but can not normally be moved endwise because of the engagement of the latch 117 with one of the grooves. Rotation of the screw shaft 115 adjusts the side walls 105 and 106 toward and from each other, and by disengaging the latch 117 from the screw shaft the latter can be moved endwise with relation to the fixed end wall 104, carrying its two side walls bodily with it.

As a guide to the operator in positioning the side walls or guides laterally with respect to the center line of the machine, I have provided a pointer or finger 122 loosely mounted upon screw shaft 115 between two pins 123 and cooperating with an index or scale 124 on end wall 104.

The above-described adjustments make it possible to adapt the magazine to different sized blanks and to the positioning of soles and other crooked blanks for proper presentation to the detecting rolls. The magazine is not herein claimed as it forms part of the subject matter claimed in another application.

The operation of the machine is as follows:

Assuming that there is a supply of soles or other blanks stacked in the magazine H, and that the main driving shaft 1 is rotating, in order to start the feeding in of the first blank the operator lifts the push rod 87, by lifting arm 57, and allows it to drop back thereby actuating the clutch controlling lever 82 to permit the clutch member 72 to engage the continuously rotating clutch member 78. This causes the shaft 74 to make one complete revolution and stop, as already explained. The single revolution of shaft 74 causes one complete reciprocation of the feed slide 94 through the arm 92 and link 93. As the feed slide moves forward the dog 96 engages the rear end of the lowermost blank in the stack and carries the blank toward the detecting rolls. During the first part of this forward movement the trip 64 is lifted by the link 93, acting through lever 98, link 100 and arm 101, so that the blank may pass underneath trip 64 to the detecting rolls 2 and 17. Thereupon the trip 64 immediately falls and rests on the top of the blank as soon as the member 97 moves out of engagement with lever 98. The same action which lifts trip 64 just before the blank enters the detecting rolls, also withdraws pawl 50 from ratchet wheel 48, by the actuation of lever 66, bell crank 68 and link 70. The pointer 45 is now free to turn to the left toward zero (Fig. 5); it is also free to turn to the right so long as there is no blank under trip roll 60 and the latter rests in the groove in the work bed, because in that position it acts through arm 57, rock shaft 56 and arm 55 to hold pawl 49 out of engagement with its ratchet 47.

When the blank enters between the detecting rolls 2 and 17, the lower roll 17 yields downwardly against the tension of spring 25 and responds to variations in thickness of the blank as the blank progresses. The movements of the lower detecting roll 17 are transmitted to pointer 45 of the visual indicator through arms 18, rods 26, cross bar 30, arms 33, rock shaft 34, arm 35, rod 36 and

segments 41, 43. None of the measurements as determined by the detecting rolls, however, will be preserved until the blank has reached and lifted the trip roller 60, because until that time both pawls 50 and 49 are disengaged and the pointer 45 is free to turn in either direction. As soon as the blank passes under the trip roller 60, the lifting of roller 60 acts through arm 57, 70 rock shaft 56, and arm 55 to let pawl 49 into engagement with ratchet 47. The pointer is now locked against moving to the right in response to any detector measurements of greater thickness but is free to move to the left to indicate any thinner spots encountered by the detector.

Just before the blank passes completely through the detecting rolls, the trip 64 drops off the rear or following end of the blank. 20 The drop of trip 64 causes the other pawl 50 to engage its ratchet 48, acting through lever 66, bell crank 68 and link 70. The pointer 45 is now locked against movement in either direction and indicates the measurement in irons of the thinnest detected spot of the blank. The operator reads the indicated grade and then withdraws the blank by hand 25 from the machine and places it in its proper bin or receptacle.

30 As soon as the blank is removed from under trip roller 60, the latter falls and then, and not until then, pawl 49 is disengaged, through arm 57 and rock shaft 56, and at the same time another reciprocation of the feed mechanism is automatically started, 35 through rock shaft 56, arm 90 and push bar 87, and the cycle of operations is repeated with relation to the next succeeding blank. Thus all that the operator is required to 40 do is to keep the feed magazine supplied with blanks and to sort or otherwise dispose of the measured blanks according to their indicated grades. The mere removal of a graded blank from the machine automatically causes a new blank to be fed into 45 the machine and graded.

I claim:

1. A grading machine comprising detecting means, grading mechanism, means 50 whereby the grading mechanism is responsive to the detecting means, feeding mechanism for feeding blanks one at a time to the detecting means, and mechanism operated automatically when the operator removes a graded blank from the machine, to actuate the feeding mechanism to feed another blank 55 into the machine.

2. A grading machine comprising detecting means, grading mechanism, means 60 whereby the grading mechanism is responsive to the detecting means, a magazine for holding a stack of blanks to be graded, normally idle feeding mechanism for feeding blanks one at a time from the magazine to 65 the detecting means, and mechanism oper-

ated automatically when the operator removes a graded blank from the machine to actuate the feeding mechanism to transfer another blank from the magazine to the detecting means. 70

3. A grading machine comprising detecting means, a grade indicator, means whereby the grade indicator is responsive to the detecting means, normally idle feeding mechanism for feeding blanks one at a time to the detecting means, a trip adapted to engage a blank at the delivery side of the detecting means, and mechanism operated by said trip upon the removal of the blank 75 from engagement therewith, to actuate the feeding mechanism to feed another blank into the machine.

4. A grading machine comprising detecting means, a grade indicator, means whereby the grade indicator is responsive to the detecting means, a lock for said indicator, normally idle feeding mechanism for feeding blanks one at a time to the detecting means, a trip for controlling said lock adapted to engage a blank at the delivery side of the detecting means, and mechanism operated by said trip upon the removal of the blank 80 from engagement therewith, to unlock said lock and to actuate the feeding mechanism to feed another blank into the machine. 85

5. A grading machine comprising detecting means, a grade indicator, means whereby the grade indicator is responsive to the detecting means, normally idle feeding mechanism for feeding blank one at a time to the detecting means, a continuously driven shaft, a normally disconnected clutch between said shaft and said feeding mechanism, a trip adapted to engage a blank at the delivery side of the detecting means, and mechanism operated by said trip upon the removal of the blank 90 from engagement therewith, to connect said clutch and thereby actuate the feeding mechanism to feed another blank into the machine. 95

6. A grading machine comprising detecting means, a grade indicator, means whereby the grade indicator is responsive to the detecting means, normally idle feeding mechanism for feeding blanks one at a time to the detecting means, including a reciprocating feed slide, a continuously driven shaft, a normally disconnected clutch between said shaft feed slide, a trip adapted to engage a blank at the delivery side of the detecting 100 means, mechanism operated by said trip upon the removal of the blank from engagement therewith, to connect said clutch and thereby reciprocate said feed slide to feed another blank into the machine, and means for automatically disconnecting said clutch at the completion of one reciprocation of the feed slide. 105

7. A grading machine comprising detecting means, grading mechanism, means 110

- whereby the grading mechanism is responsive to the detecting means, means for locking the grading mechanism in accordance with the thinnest detected spot of the blank 5 operated upon, feeding mechanism for feeding blanks one at a time to the detecting means, a trip adapted to engage a blank at the delivery side of the detecting means, and mechanisms operated by said trip upon 10 the removal of the blank from engagement therewith, to disengage said locking means and to actuate the feeding mechanism to feed another blank into the machine.
8. A grading machine comprising detecting rolls, a grade indicator, mechanism through which the detecting rolls adjust the indicator in accordance with the thinnest detected spot of the blank operated upon, said mechanism including a locking pawl, a trip 15 adapted to engage a blank at the delivery side of the detecting rolls for controlling said locking pawl, a magazine for holding a stack of blanks to be graded, a reciprocating feed slide to transfer blanks one at a time from the magazine to the detecting 20 rolls, a continuously driven shaft, a normally disconnected clutch between said shaft and feed slide, mechanisms operated by said trip 25 adapted to engage a blank at the entrance side of the detecting rolls, a continuously driven shaft, a clutch between said shaft and feed slide, mechanism operated by the trip at the entrance side of the detecting rolls to engage a locking pawl and to connect said clutch and thereby 30 reciprocate said feed slide to feed another blank into the machine, and means for automatically disconnecting said clutch at the 35 completion of one reciprocation of the feed slide.
9. A grading machine of the kind having detecting means, grading mechanism, means whereby the grading mechanism is responsive to the detecting means and a pawl-operating trip in the path of the blank at the delivery side of the detecting means, combined with a reciprocating feed slide, a continuously driven shaft, a clutch between said 40 shaft and feed slide, a cam arm normally holding said clutch disconnected, a push bar actuated by said trip adapted to swing the cam so as to permit the clutch to connect the continuously driven shaft and the feed 45 slide to reciprocate the latter, and means for automatically disconnecting the clutch and restoring the cam arm to normal position at the completion of one reciprocation of the feed slide.
- 50 10. A grading machine of the kind having detecting means, grading mechanism, means whereby the grading mechanism is responsive to the detecting means and a pawl-operating trip adapted to rest on the blank at the delivery side of the detecting means, combined with a reciprocating feed slide, a shaft 55 normally at rest having a crank arm and a link connecting the crank arm to the feed slide, a continuously rotating clutch member loose on said shaft, an opposed clutch 60 member splined on said shaft, a spring urging the splined clutch member toward the other clutch member, a cam arm normally holding the splined clutch member disconnected from the other clutch member, a 70 push bar actuated by the drop of the trip when the blank is removed from underneath the trip, to disengage the cam arm from the splined clutch member and permit the clutch members to engage and thereby reciprocate 75 the feed slide, and means for automatically disconnecting said clutch members and restoring said cam arm to normal position at the completion of one reciprocation of the feed slide.
- 80 11. A grading machine of the kind having a detector, grading mechanism, means whereby the grading mechanism is responsive to the detector and a trip adapted to rest on the blank at the delivery side of the detector and adapted while held up by the blank to preserve in the grading mechanism the measurement of the thinnest detected spot of the blank, combined with means to lock the grading mechanism in its adjusted 85 position at the end of the detecting operation, a vertically movable trip in the path of the blank at the entrance side of the detector to control the lock, a reciprocating feed slide, a continuously driven shaft, a normally disconnected clutch between said shaft and feed slide, mechanism operated by the trip at the delivery side of the detector, when the blank is removed from under the trip to connect 90 said clutch and thereby reciprocate the feed slide to feed another blank into the machine, and means actuated by the feeding operation 95 to raise the trip at the entrance side of the detector as the blank approaches the detector and again to drop it on top of the advancing blank, said trip adapted to lock its lock when it drops off the end of the blank.
- 100 12. In a grading machine of the class described, detecting rolls, a grade indicating pointer, means through which the detecting rolls set the pointer in accordance with the thinnest spot of the blank as determined by the detecting rolls, two locks, one to prevent the turning of the pointer in one direction and the other to prevent the turning of the pointer in the other direction, a trip in the path of the blank at the entrance side of the detecting rolls for controlling one of said locks and adapted to hold its lock disengaged while the trip rests on the blank, a 110 trip in the path of the blank at the delivery side of the detecting rolls for controlling the other lock and adapted to hold its lock engaged while the trip rests on the blank, a reciprocating feed slide, means controlled by 115 the trip at the delivery side of the detecting rolls for operating the feed slide when the blank is removed from under said trip, means actuated by the feeding operation to 120 raise the trip at the entrance side of the detecting rolls for operating the feed slide when the blank is removed from under said trip, means actuated by the feeding operation to 125 raise the trip at the entrance side of the detecting rolls for operating the feed slide when the blank is removed from under said trip, means actuated by the feeding operation to 130 raise the trip at the entrance side of the detecting rolls for operating the feed slide when the blank is removed from under said trip,

tecting rolls as a blank approaches the detecting rolls and then to drop it on top of the advancing blank, said last-named trip adapted to lock its lock when it drops off the 5 end of the blank.

13. In a machine of the class described, in combination, a reciprocating feed slide for feeding blanks one by one into the machine, a drive shaft, actuating connections between 10 said drive shaft and the feed slide including a friction element adapted positively to actuate the feed slide during normal operation of the machine but to slip in the event of the clogging of the feed slide, a driving 15 member loose on said shaft, power means for continuously rotating said driving member, and manually operated means for connecting and disconnecting said driving member and drive shaft, whereby the shaft may be 20 continuously driven by the power means or disconnected from and turned independently of the power means.

14. In a machine of the class described, means for detecting the grade of a blank 25 with reference to the thinnest spot of the area being measured, a grade indicator, means whereby the grade indicator is responsive to the detecting means, automatic means for locking the grade indicator in accordance with the thinnest spot detected, 30 normally idle feeding mechanism and actuating means therefor adapted to feed blanks one at a time to the detecting means, and means under the control of the operator 35 to unlock the grade indicator in preparation for the next blank and simultaneously to operate the feeding mechanism to feed another blank to the detecting means, whereby 40 the time of such unlocking of the indicator and of the feeding in of another blank may be determined wholly by the operator.

15. A grading machine comprising detect-

ing means, grading mechanism, means whereby the grading mechanism is responsive to the detecting means, a lock for said 45 grading mechanism, a lever arm and a trip adjustably mounted thereon for controlling said lock, the trip being adapted to engage a blank at the delivery side of the detecting means, and a work support over which the 50 blanks move at the delivery side of the detecting means, said work support having a groove or channel gradually increasing in depth in the direction of travel of the work in which said adjustable trip rests, whereby 55 a blank moving over said work support and under said trip will impart to the lever arm substantially the same angular movement irrespective of the position of adjustment of the trip on the lever arm. 60

16. A grading machine comprising detecting means, grading mechanism, means whereby the grading mechanism is responsive to the detecting means, a lock for said 65 grading mechanism, a lever arm and a trip adjustably mounted thereon for controlling said lock, the trip being adapted to engage a blank at the delivery side of the detecting means, and a work support over which the 70 blanks move at the delivery side of the detecting means, said work support being inclined upwardly in the direction of travel of the work and having a groove or channel in which said adjustable trip rests, the bottom of said groove or channel being horizontal, whereby a blank moving over said 75 work support and under said trip will impart to the lever arm substantially the same angular movement irrespective of the position of adjustment of the trip on the lever 80 arm.

Signed by me at Manchester, New Hampshire, this 16th day of March, 1927.

LEANDER A. COGSWELL.
